(57) **CLAIM**

The ornamental design for a display screen for a digital camera with a transitional graphical user interface, as shown and described.

DESCRIPTION

FIG. 1 is a first image of a display screen for a digital camera with a transitional graphical user interface showing my new design;

FIG. 2 is a second image thereof;

FIG. 3 is a third image thereof;

FIG. 4 is a fourth image thereof;

FIG. 5 is a fifth image thereof; and,

FIG. 6 is a sixth image thereof.

The appearance of the image transitions sequentially between the images shown in FIGS. 1-6. The process or period in which an image transitions to another forms no part of the claimed design.

The broken line showing of a display screen and graphic elements in all views forms no part of the claimed design.
